DESIGN FOR A COAT

Joseph M. Riordan, San Francisco, Calif., assignor to Gantner & Mattern Company, San Francisco, Calif., a corporation of California

Application June 6, 1938, Serial No. 77,631

Term of patent 7 years

To all whom it may concern:

Be it known that I, Joseph M. Riordan, a citizen of the United States, residing at the city and county of San Francisco, State of California, have invented a new, original, and ornamental Design for a Coat, of which the following is a specification, reference being had to the accompanying drawing, forming a part thereof.

In the drawing Fig. 1 is a front view of a coat, showing my new design.

Fig. 2 is a rear view of the coat shown in Fig. 1.

I claim:

The ornamental design for a coat, as shown.

JOSEPH M. RIORDAN.
